UNITED STATES PATENT OFFICE.

JAMES R. JONES, OF JOHNSTOWN, PENNSYLVANIA.

MOLD AND METHOD OF MAKING THE SAME.

Application filed November 30, 1927. Serial No. 236,696.

This invention relates to molds and the method of making said molds, and more particularly to molds used in casting the splice bar ends of switch pieces, frogs and other 5 railway track structure parts, and has for its object the provision of a novel form of mold including a separate core piece carrying the bolt hole cores.

Heretofore the practice has been to make a 10 separate mold-piece to form each side of the splice bar end of a railway track structure part and it is next to impossible to set these individual mold-pieces into the main mold so that they will be correctly spaced and alined. 15 When bolt holes are to be cored by the old practice print holes were formed into which plugs were mounted to form the bolt hole cores and if the mold-pieces were not properly spaced and alined, the bolt holes would 20 be inaccurate.

The structures cast by the use of the mold-pieces as heretofore formed were in many cases inaccurate so as to compel the alternating thereof by welding and grinding which 25 added greatly to their cost of manufacture.

The present invention eliminates all the 30 troubles resulting from the incorrect spacing and alining of the old form of mold-pieces and provides a single mold piece which, with ordinary skill, will produce perfectly formed 35 castings.

In the drawings—

Figure 1 is a sectional view through a box 40 in which the mold is formed in accordance 45 with this invention.

Figure 2 is a perspective view of a bolt hole 50 core piece.

Figure 3 is a plan view of the mold formed 55 as shown in Figure 1 and having the bolt hole core mounted therein.

Figure 4 is a side elevation thereof.

Figures 5, 6, and 7 show end elevations 60 of molds for various forms of rail shapes.

Referring more particularly to the drawings, the numeral 2 designates the mold box in which the mold 3 is formed. A suitable pull-out rail or pattern 4 is mounted in the mold box 2 and the U-shaped arbor 5 is also mounted in the box 2 with its closed end extending around the point end of the pull-out rail. After the pull-out rail 4 and arbor 5 are thus assembled in the box 2 the sand or other core forming material is rammed into the box around the pull-out rail and arbor so as to 65 form the one-piece mold 3.

The pull-out rail or pattern is provided on

its one side face with projection or print portion 6 extending along its entire length so as to form a print or recess 7 in the side face of the mold cavity 8 of the main core when the 60 pull-out rail is removed. The recess 7 is adapted to receive a core member B composed of a substantially flat rectangular body portion 8 of a size to snugly fit into and fill the recess 7 and having a plurality of bolt hole 65 core projections 9 formed integrally therewith.

The core B is adapted to be separately 70 formed and to be inserted or mounted into the recess 7 of the finished mold 3.

The core B will be secured against displacement by nails 10 as is common in the molding art.

It will be understood that the core B may have any number of bolt hole cores 9 thereon 75 necessary to form the bolt holes in the casting, and if desired or necessary, two or more of such cores may be used.

In Figure 5 a mold structure is shown for use in casting T-head rail sections, in this 80 mold the core B being positioned at the top of the mold cavity.

In Figure 6 a mold structure is shown for use in casting what is known as nine inch 85 girder rails. These rail ends have two rows of bolt holes and two cores B are used, one of which is mounted in each side face of the mold cavity, one for the upper and one for the lower row of holes.

In Figure 7 a modified mold construction 90 is shown for casting the same type of rail end as shown in Figure 6. In this construction the mold cavity 8 is formed of a greater width than the web of the rail and one core is mounted in the cavity and forms the entire 95 one face thereof, while the other face of the mold cavity is recessed and a second core 9 is mounted in the recess.

By constructing molds in accordance with this invention the resulting castings will be 100 true and the bolt holes will be correctly formed and located so that a minimum of work will be necessary to finish such castings for use. This is especially advantageous when making manganese steel castings since 105 it is impractical to bore or ream the bolt holes in such castings and all other finishing work is difficult and expensive.

I claim—

1. A mold for use in casting the splice bar 110 ends of switch pieces, frogs and other railway track structure parts having bolt holes cored

- therein, comprising a one-piece **U**-shaped mold body having a complete mold cavity formed therein and at least one recess formed in at least one side face of said mold cavity,
5 a **U**-shaped arbor mounted in said mold body, a core-piece mounted in said recess, nails projecting through said core-piece and into said mold body for preventing displacement of said core-piece, said core comprising a body portion of such size as to snugly fit into and fill said recess, and at least one bolt hole core formed integral with said body portion of said core and extending entirely across said mold cavity in said mold body.
10 2. The method of forming molds for use in casting the splice bar ends of switch pieces, frogs and other railway track structure parts having bolt holes cored therein, which consists in mounting a **U**-shaped arbor in a mold
15

box, then mounting a pull-out rail having at least one projection extending lengthwise along at least one side face in said box and within said **U**-shaped arbor, then direct ramming mold forming material such as sand in the mold box around said pull-out rail and arbor until said box is completely filled to form a complete mold body, pulling out said pull-out rail so as to form a mold cavity having a recess in its one side face corresponding to said projection on the one side face of said pull-out rail, then forming a core of a size substantially equal to said recess and having at least one integral bolt hole core thereon, then mounting said core in said recess, and securing said core against displacement.

25 In testimony whereof, I have hereunto signed my name.

30 JAMES R. JONES.
